FIG. 1

FIG. 3

FIG. 4

FIG. 5

FIG. 1 is a view in perspective of the weight box mounted on the front end of a tractor, the tractor being shown in dotted lines;

FIG. 2 is an enlarged view in side elevation as seen from the left side thereof, the right side being a mirror image of said left side;

FIG. 3 is a view in top plan thereof;

FIG. 4 is a view in bottom plan thereof; and

FIG. 5 is a view in rear elevation thereof.

The dotted line showing of FIG. 1 is for illustrative reasons only and does not form a part of the design.

We claim:

The ornamental design for a detachable weight box for the front end of tractors, as shown and described.
